CLAIM

The ornamental design for a hay feeder bag as shown and described.

DESCRIPTION

FIG. 1 is a front and left perspective view of a hay feeder bag showing my new design;

FIG. 2 is a front perspective view thereof;

FIG. 3 is a rear perspective view thereof;

FIG. 4 is a right perspective view thereof;

FIG. 5 is a left perspective view thereof;

FIG. 6 is a top perspective view thereof;

FIG. 7 is a bottom perspective view thereof;

FIG. 8 is a rear and right perspective view thereof; and, FIG. 9 is a front, left perspective view of the hay feeder bag, shown in an open configuration.

The broken lines shown in FIG. 1, 2, 6, 7 and FIG. 9 represent stitching and do form part of the claimed design.
